WALTER T. ABEL, OF WATERBURY, CONNECTICUT, ASSIGNOR TO THE PATENT BUTTON COMPANY, OF WATERBURY, CONNECTICUT, A CORPORATION OF CONNECTICUT.

METHOD OF MAKING ONE-PIECE METAL BUTTONS.

Application filed October 23, 1924. Serial No. 745,329.

To all whom it may concern:

Be it known that I, WALTER T. ABEL, a citizen of the United States, and a resident of Waterbury, in the county of New Haven 5 and State of Connecticut, have made and invented certain new and useful Improvements in Methods of Making One-Piece Metal Buttons, of which the following is a specification.

10 My invention relates to a method of making a one-piece metal button. The object of my invention is to provide a method of forming a one-piece metal button by the combined heading and extruding process 15 and to produce by such process a button which will be of any desired or irregular configuration and will bear thereon any suitable inscription or ornamentation, and, furthermore, the head of the button will be 20 entirely free of any bur or fin.

Heretofore the objection to forming a button by a heading process was not only due to the presence of a bur or fin resulting from such process, but was also due to the 25 difficulty in making suitable provision for the metal which must be displaced from one end of the blank so as to form a hollow hub. By my novel method, I have overcome these objections and difficulties by causing a portion 30 of the metal which is located at one end of the blank to flow up into the head forming portion or opposite end of the blank when the latter is contained within a closed and head-forming die chamber. A 35 hollow hub is accordingly produced; and, further, the metal by flowing into the head-forming die chamber when the latter is closed produces a button head which is entirely free of any bur or fin.

40 A further object is to provide a novel heading process for the formation of a one-piece button which includes the use of two dies, which when brought together form a chamber of the size and shape of the desired button; and a third extruding or plunger die which is adapted to act upon the rod-like blank which is contained within the die chamber and expand it to completely fill the die chamber and thereby produce a one- 45 piece button, the third or extruding die not

acting until the first two dies have been brought together.

With the foregoing and other objects in view, my invention consists in the improved method of forming a one-piece metal button illustrated in the accompanying drawings and hereinafter described and claimed and in such variations and modifications thereof as will be obvious to those skilled in the art to which my invention relates, it 55 being understood that changes may be made within the scope of what is claimed without departing from the spirit thereof.

The preferred embodiment of my invention is disclosed in the accompanying drawings, wherein:

Figure 1 is a view in elevation of the first stage blank;

Figure 2 is a view in section of a second stage blank or partially formed button;

Figure 3 is a sectional view of the completed button;

Figure 4 is a view in longitudinal section of the dies and supplementary mechanism for transforming the first-stage blank into the second stage blank, the dies being illustrated in their separated or open position;

Figure 5 is a similar view showing the die blocks having been forced together but prior to the movement of the extruding 80 plunger;

Figure 6 is a similar view after the extruding plunger has been moved inwardly and illustrating the completed formation of the second stage blank; and

Figure 7 is a view of the closing dies used to finish the end wall of the hub and thereby complete the formation of the button.

My novel method of forming a button or similar article consists in cutting to the proper length a rod like blank as illustrated in Figure 1 and by the usual mechanisms employed in heading machines moving it into the die chambers of the die blocks illustrated in Figure 4. The die blocks illustrated in Figure 4 consist of the stationary block 10 having the chamber or cavity 11 therein, the same being characterized by a reduced or hub forming portion 12 and an enlarged and head forming portion 100

13, and a second and movable die block 14 which is provided with the head forming cavity or chamber 15 which is adapted when the dies are together to register and form a 5 smooth continuation of the head forming cavity 13 of the die block 10. The die block is illustrated as being moved by a cam 16. This mechanism, however, may be modified or varied in any way so as to 10 produce the required movement of the die block 14, as I do not wish to limit myself to the use of a cam to accomplish the same.

The die block 10 is provided with a longitudinal bore or opening A, which 15 communicates with but is relatively smaller in diameter than the chamber 12 and in which opening or bore A extends a plunger or extruding die 17. This plunger or extruding die is controlled in its movements by a 20 cam 18, although here again it is to be understood that other mechanisms such as a crank arm and suitable linkage may be employed to produce the desired motion and timing of the extruding die or plunger 17. 25 The cams 16 and 18 are connected through suitable gearing (not shown) whereby the movable die block 14 will approach and contact with the die block 10, and will, for a small interval of time, remain fixed in 30 such position, at and during which time the extruding die or plunger 17 will be forced rapidly forward and then withdrawn by a spring 17' or other suitable device.

With the mechanism as thus arranged, the 35 blank of Figure 1 is moved into the space between the die blocks 10 and 14 and occupies a position as illustrated by dotted lines in Figure 4. The blank of Figure 1 contains a predetermined amount of metal so 40 that as the heading die 14 approaches and contacts with the stationary die 10, the metal of the blank will be forced into the button forming cavity 12, 13 and 15, and will produce the partially formed button or blank 19 as illustrated in Figure 5. The amount of 45 work done by the moving die block 14 depends entirely upon the configuration and shape of the button. In some instances the greater portion of the heading will be accomplished by the moving die block 14 and in other instances the blank will not be in 50 any way affected as the metal to be extruded or forced from the hub portion of the blank will be sufficient to form the entire head. In either instance the head forming cavity 13, 15, will be characterized by 55 smooth and continuous side walls prior to the forming of the head of the button.

With the dies 10 and 14 together as illustrated in Figure 5, a plunger or extruding die 17 under the action of the cam 18 is moved rapidly forward and forces 60 itself into the metal of the blank and produces a cavity 20 therein. As the plunger 65 forces its way into the blank and produces

the cavity 20, the metal is displaced and caused to flow up into the front or head forming portion of the blank, and at which place it expands so as to completely fill the head forming chamber 13, 15. The die 70 blocks being rigidly held together by the cam 16 prevent any metal of the head of the button being forced between the contacting and confronting surfaces of the die block so that a one-piece button, composed of a hollow hub and an enlarged head, is formed and will be completely free of any burs or fins. Advantage is taken of the 75 fact that a button is desired having a hollow hub and the displaced metal is utilized 80 to form a head having any desired configuration.

The second stage blank as thus formed and as illustrated in Figure 6 is then subjected to the action of a second set of dies 85 as illustrated in Figure 7. These dies include the head receiving block 21 and the hub receiving block 22, the latter being formed with an inwardly tapering cavity 90 23, the side walls of which are adapted to contact with the end of the hollow hub, and inwardly turn or taper the walls of the hub so as to form the completed button as illustrated in Figure 3.

My improved method is particularly important in the formation of a button having an irregularly shaped head, as with this style of button it is practically impossible to remove a fin or feathered edge 95 were it to occur around the head of the button and as would be produced by the ordinary heading process. While I am aware that it is old to provide a heading process for forming buttons yet such processes have always resulted in the formation 100 of a feathered edge and have not utilized the metal which normally resides in the hub forming portion of the blank in the manner described above. In my novel process I displace the metal from the one end of the 105 blank and thereby form a hollow hub and at the same time cause this metal to flow into the opposite end of the blank and completely fill a closed die chamber, and thereby 110 form the button head.

Having thus described my invention what I claim is:—

1. The method of forming an article comprising a head and a hollow shank consisting in subjecting a rod-like blank to the action of heading dies and only partially forming the head and subjecting the shank portion of the blank to the action of a plunger while the heading dies are closed and displacing the metal from the center of the shank and causing it to flow into the head to thereby complete the head.
2. The method of forming an article comprising a head and a hollow shank consisting in subjecting a rod-like blank to the 120

action of heading dies and only partially the hollow hub to the action of a closing forming the head, and subjecting the shank die thereby contracting the outermost end portion of the blank to the action of a of said hub. Signed at Waterbury in the county of 5 plunger while the heading dies are closed. Signed at Waterbury in the county of and displacing the metal from the center of New Haven and State of Connecticut this the shank and causing it to flow into the 17th day of October A. D. 1924. head to complete the same and subjecting

WALTER T. ABEL.
